DISPLAY RACK FOR BELTS

Martin Aronson, New York, N. Y.

Application April 5, 1954, Serial No. 29,831

Term of patent 14 years

(Cl. D80—9)

To all whom it may concern:

Be it known that I, Martin Aronson, a citizen of the United States, residing in the city of New York, county of Queens and State of New York, have invented a new, original, and ornamental Design for a Display Rack for Belts, of which the following is a specification, reference being had to the accompanying drawings, forming a part hereof, in which:

Fig. 1 is a front elevation of a display rack for belts embodying my new design.

Fig. 2 is an exploded view of the same and showing the upper section in raised position.

Fig. 3 is a plan view of the upper removable section.

Fig. 4 is a plan view of the lower or base section.

Fig. 5 is a section taken on line 5—5 of Fig. 4.

I claim:

The ornamental design for a display rack for belts, as shown.
